(57) **CLAIM**

The ornamental design for a carton for infusion bags, as shown and described.

DESCRIPTION

The patent or application file contains at least one drawing executed in color. Copies of this patent or patent application publication with color drawing will be provided by the Office upon request and payment of the necessary fee.

FIG. 1 is a top perspective view of a carton for infusion bags, showing our new design;

FIG. 2 is a bottom perspective view of the carton of FIG. 1.

FIG. 3 is a right side view of the carton of FIG. 1.

FIG. 4 is a front view of the carton of FIG. 1.

FIG. 5 is a left side view of the carton of FIG. 1.

FIG. 6 is a back view of the carton of FIG. 1.

FIG. 7 is a top view of the carton of FIG. 1.

FIG. 8 is a bottom view of the carton of FIG. 1.

FIG. 9 is a top perspective view of a carton for infusion bags, showing our new design;

FIG. 10 is a bottom perspective view of the carton of FIG. 9.

FIG. 11 is a right side view of the carton of FIG. 9.

FIG. 12 is a front view of the carton of FIG. 9.

FIG. 13 is a left side view of the carton of FIG. 9.

FIG. 14 is a back view of the carton of FIG. 9.

FIG. 15 is a top view of the carton of FIG. 9.

FIG. 16 is a bottom view of the carton of FIG. 9.

FIG. 17 is a top perspective view of a carton for infusion bags, showing our new design;

FIG. 18 is a bottom perspective view of the carton of FIG. 17.

FIG. 19 is a right side view of the carton of FIG. 17.

FIG. 20 is a front view of the carton of FIG. 17.

FIG. 21 is a left side view of the carton of FIG. 17.

FIG. 22 is a back view of the carton of FIG. 17.

FIG. 23 is a top view of the carton of FIG. 17.

FIG. 24 is a bottom view of the carton of FIG. 17.

FIG. 25 is a top perspective view of a carton for infusion bags, showing our new design;

(Continued)

FIG. 26 is a bottom perspective view of the carton of FIG. 25.

FIG. 27 is a right side view of the carton of FIG. 25.

FIG. 28 is a front view of the carton of FIG. 25.

FIG. 29 is a left side view of the carton of FIG. 25.

FIG. 30 is a back view of the carton of FIG. 25.

FIG. 31 is a top view of the carton of FIG. 25.

FIG. 32 is a bottom view of the carton of FIG. 25.

FIG. 33 is a top perspective view of a carton for infusion bags, showing our new design;

FIG. 34 is a bottom perspective view of the carton of FIG. 33.

FIG. 35 is a right side view of the carton of FIG. 33.

FIG. 36 is a front view of the carton of FIG. 33.

FIG. 37 is a left side view of the carton of FIG. 33.

FIG. 38 is a back view of the carton of FIG. 33.

FIG. 39 is a top view of the carton of FIG. 33.

FIG. 40 is a bottom view of the carton of FIG. 33.

FIG. 41 is a top perspective view of a carton for infusion bags, showing our new design;

FIG. 42 is a bottom perspective view of the carton of FIG. 41.

FIG. 43 is a right side view of the carton of FIG. 41.

FIG. 44 is a front view of the carton of FIG. 41.

FIG. 45 is a left side view of the carton of FIG. 41.

FIG. 46 is a back view of the carton of FIG. 41.

FIG. 47 is a top view of the carton of FIG. 41.

FIG. 48 is a bottom view of the carton of FIG. 41.

FIG. 49 is a top perspective view of a carton for infusion bags, showing our new design;

FIG. 50 is a bottom perspective view of the carton of FIG. 49.

FIG. 51 is a right side view of the carton of FIG. 49.

FIG. 52 is a front view of the carton of FIG. 49.

FIG. 53 is a left side view of the carton of FIG. 49.

FIG. 54 is a back view of the carton of FIG. 49.

FIG. 55 is a top view of the carton of FIG. 49.

FIG. 56 is a bottom view of the carton of FIG. 49.

FIG. 57 is a top perspective view of a carton for infusion bags, showing our new design;

FIG. 58 is a bottom perspective view of the carton of FIG. 57.

FIG. 59 is a right side view of the carton of FIG. 57.

FIG. 60 is a front view of the carton of FIG. 57.

FIG. 61 is a left side view of the carton of FIG. 57.

FIG. 62 is a back view of the carton of FIG. 57.

FIG. 63 is a top view of the carton of FIG. 57.

FIG. 64 is a bottom view of the carton of FIG. 57.

FIG. 65 is a top perspective view of a carton for infusion bags, showing our new design;

FIG. 66 is a bottom perspective view of the carton of FIG. 65.

FIG. 67 is a right side view of the carton of FIG. 65.

FIG. 68 is a front view of the carton of FIG. 65.

FIG. 69 is a left side view of the carton of FIG. 65.

FIG. 70 is a back view of the carton of FIG. 65.

FIG. 71 is a top view of the carton of FIG. 65.

FIG. 72 is a bottom view of the carton of FIG. 65.

FIG. 73 is a top perspective view of a carton for infusion bags, showing our new design;

FIG. 74 is a bottom perspective view of the carton of FIG. 73.

FIG. 75 is a right side view of the carton of FIG. 73.

FIG. 76 is a front view of the carton of FIG. 73.

FIG. 77 is a left side view of the carton of FIG. 73.

FIG. 78 is a back view of the carton of FIG. 73.

FIG. 79 is a top view of the carton of FIG. 73; and,

FIG. 80 is a bottom view of the carton of FIG. 73.

The broken lines are shown for the purpose of illustrating parts of the article that form no part of the claimed design. The INFUGEM™ logo in the drawings, forming no part of the claimed design, is a registered trademark of Sun Pharmaceutical Industries Limited.
